DRINKING CUP

George Francis Hogan, Chicago, Ill.

Application January 27, 1932, Serial No. 589,137

6 Claims. (Cl. 229—1.5)

This invention relates to drinking cups and is concerned particularly with improvements in the paper drinking cups now in current use.

Paper drinking cups as usually made are tapered from top to bottom, some being made conical in shape, others being made flat with tapering sides and still other forms having a frusto-conical shape. These paper drinking cups are usually dispensed from a holder in which the cups are secured in telescoped or stacked relation and are so held in the holder that one cup may be withdrawn at a time, usually the lower one. The paper cups are also usually coated with paraffine and have a smooth surface. Difficulty is frequently experienced in abstracting one of the cups from its holder, primarily because the sloping sides thereof prevent the user from obtaining a good grip thereon. Also, the smooth paraffine-coated surface thereof provides little purchase for the grasp of the user.

It is the principal object of this invention to provide a drinking cup of the usual type and form with means whereby it may be more readily grasped and especially more easily withdrawn from the usual type of holder or dispenser in which it is supplied to the user.

This object is obtained in a preferred embodiment of the invention which comprises a paper drinking cup of any desired form or shape, whether flat, conical or frusto-conical, and having on its surface at the point where it is grasped by the user, one or more projections, preferably consisting of embossments pressed through the paper of the cup when it is formed in the dies or other forming devices. These embossments preferably take the form of crescents, circles, ridges, or the like, and are preferably located in the surface of the cup adjacent its lower portion or wherever the user grasps it to remove it from the holder or dispenser or in utilizing it in the usual way for filling and drinking purposes.

For a better understanding of this invention reference is made to the accompanying drawing, in which

Figure 1 illustrates a drinking cup embodying this invention mounted in a standard form of dispenser;

Fig. 2 illustrates a conical drinking cup embodying this invention;

Fig. 3 is an enlarged cross-section through one of the projections embossed on the surface of the drinking cup, as seen along the line 3—3 of Fig. 2;

Fig. 4 illustrates a different form of drinking cup embodying this invention;

Figs. 5 and 6 illustrates modified forms of the invention; and

Fig. 7 is an enlarged section through one of the embossments as seen along the line 7—7 of Fig. 5.

In Figs. 1 and 2 of this drawing is illustrated a conical paper drinking cup 10, having formed on the surface thereof adjacent its lower end a plurality of projections 11 arranged in rows. These projections 11 are formed on the cup at the point where the paper is of double thickness, so that the hole in the outer layer produced by the embossing operation does not cause the cup to leak. These embossments are formed in the paper at the proper points before or during the cup-forming operation. These embossments are preferably crescent-shaped in plan, as shown in Figs. 1 and 2 and are spur-like in shape when viewed in cross-section, as shown in Fig. 3 which also illustrates how the inner layer of paper seals the hole formed in the outer layer by the embossment 11.

These projections roughen the otherwise smooth surface of the cup at the point where it is grasped by the user either in withdrawing it from the holder or while holding it for filling and drinking purposes. It will be seen that when the cup 10 is mounted in the usual dispenser 12, as illustrated in Fig. 1, it may be more readily grasped and withdrawn because of the projections 11 on its surface in spite of the taper and smoothness of the cup, which ordinarily makes it difficult to grasp and withdraw from the dispenser 12.

Paper drinking cups of other conventional forms and shapes may also be provided with these embossed projections. For example, Fig. 4 illustrates a flat paper drinking cup of tapered shape, which is supplied in flattened condition and has to be opened by the user before liquid can be introduced therein. These flat cups are usually stacked in a vertical dispenser in flat condition and are withdrawn by the frictional engagement of the user's fingers with one flat surface thereof, usually the lower surface. Because of the smooth surface of the cup and the weight of the stack of cups resting on this lowermost cup, it is frequently difficult to withdraw it from the dispenser without considerable effort. In accordance with this invention, the flat tab 14 of the cup 13, shown in Fig. 4 is provided with the projections 11' embossed in the paper. The tab 14 is embossed so that the double thickness of paper will prevent leakage in the manner described and illustrated in Fig. 3. These embossments 11' on the lower surface of the cups as

they are mounted in the dispenser aid the user to withdraw a cup therefrom by providing a frictional gripping surface on the cup. These embossments 11' also permit a firmer grip on the 5 cup for filling and drinking purposes after it has been opened for use.

In another form of flat cup 15 illustrated in Fig. 5 the cup has little area of double thickness and the embossments 16 are formed in the paper 10 without perforating the same, as shown in the section of Fig. 6, which is taken through one of these embossments 16. This method of roughening the surface of paper cups may also be applied to the cup shown in Figs. 1 to 4, inclusive, 15 since it is not necessary, but only more convenient, to place the embossments in the outer layer of the two-ply area illustrated by Fig. 3.

The more rigid frusto-conical paper cup illustrated in Fig. 6 may also be provided with 20 the embossed projections 11" for the same purpose.

It will be seen that the use of the ordinary paper drinking cups of various forms and shapes is made easier by the present invention and many 25 of the objections to these cups as formerly provided are obviated. These embossed projections on the cups may be arranged anywhere on the surface thereof, depending upon requirements, and may be of any shape or form other than the 30 crescent shape illustrated and described herein. These embossments can be formed when the cup is being pressed into shape or afterward, and in no way interfere with the strength or efficacy of the cups and are so shaped as to permit ready 35 separation of the nested cups and prevent them from sticking together.

While a preferred embodiment of the invention has been described herein it is to be understood that it is not limited thereby but is susceptible of changes in form and detail within 40 its scope.

I claim:

1. As a new article of manufacture, a drinking cup of flexible material having projections 45

formed on the outer surface thereof by distortion of the paper, said distortions being sufficient in number and sufficiently close together to provide a gripping portion from which one's fingers will not readily slip.

80

2. As a new article of manufacture, a paper drinking cup having projections embossed on the surface thereof adjacent its lower end, the embossments of said surface being sufficient in number and sufficiently close together to provide a gripping portion from which one's fingers will not readily slip.

85

3. As a new article of manufacture, a paper drinking cup having sets of projections on diametrically opposite surfaces thereof formed by distortion of the paper, said distortions being sufficient in number and sufficiently close together to provide gripping portions from which one's fingers will not readily slip.

90

4. As a new article of manufacture, a flat paper drinking cup adapted to be opened by the user and having at least one surface thereof roughened by distortion of the paper, said distortions being sufficient in number and sufficiently close together to provide a gripping portion 100 from which one's fingers will not readily slip.

95

5. As a new article of manufacture, a flat paper drinking cup adapted to be opened by the user and having projections embossed on at least one flat surface thereof, said projections being 105 sufficient in number and sufficiently close together to provide a gripping portion from which one's fingers will not readily slip.

100

6. As a new article of manufacture, a paper cup having at least a portion comprising a plurality of layers of the paper, and projections embossed in the outer layer of paper, said projections being sealed against leakage by the inner layer of the paper and being sufficient in number and sufficiently close together to provide a 115 gripping portion from which one's fingers will not readily slip.
